UNITED STATES PATENT OFFICE.

PETER DRAUTZBURG, OF CINCINNATI, OHIO.

LIQUID-GAGE.

1,075,025.

Specification of Letters Patent.

Patented Oct. 7, 1913.

Application filed March 21, 1913. Serial No. 756,000.

To all whom it may concern:

Be it known that I, PETER DRAUTZBURG, a citizen of the United States, residing at Cincinnati, in the county of Hamilton and State of Ohio, have invented new and useful Improvements in Liquid-Gages, of which the following is a specification.

This invention relates to liquid gages for casks, barrels or like receptacles; and 10 it has for its primary object the provision of a tube which may be arranged in direct communication with the receptacle so that the level of the liquid will be clearly visible at all times, and further the association of 15 the tube with a scale or graduated bar whereby the gage may be effectually used to accurately measure the portion of liquid during the operation of drawing the liquid from the receptacle.

20 Another object of the invention is the provision of a liquid gage which may be connected with any standard form of cask and arranged through a convenient and simple form of connecting member with 25 the faucet so that the required communication between the tube and the cask is established.

With these and other objects in view, the 30 invention consists of certain novel features of construction, combination and arrangement of parts, as will be hereinafter described and claimed.

In the accompanying drawings: Figure 1 is a side view of the gage, showing the 35 application of the same to a cask; Fig. 2 is a section on line 2—2 of Fig. 1; Fig. 3 is a section on line 3—3 of Fig. 1; and Fig. 4 is a section on line 4—4 of Fig. 1.

The device comprises a tube holder 1, 40 which is preferably constructed of metal stamped in its main length to form a vertical channel 2 having one of its walls provided with embracing fastening devices 3 which may be sprung across the 45 channel and made to impinge against the tube 4 and thereby hold the latter against lateral displacement. The lower end of the channel may be closed by an integral seat 5, against which the bottom of the 50 tube is designed to rest. The tube holder has its wall 6 offset into a gage bar 7 which extends throughout the length of the tube and which is graduated at 8 so that a quantity of liquid within the cask may 55 be readily ascertained exteriorly and the liquid measured while the latter is drawn off.

At the upper end the bar 1 is provided with a lateral threaded stud 9 which extends through a vertical elongated slot 10 in the lower end of the clamping hook 11. 60 At the opposite end the bar 7 is provided preferably with an integral hook 12, the latter being designed to fit over the lower edge of the cask, while the clamp 11 as is 65 obviously seen on reference to Figs. 1 and 3 is adapted to be arranged over the upper edge of the cask and then adjusted so that the tube holder is vertically disposed and operatively mounted. The stud 9 carries a clamping nut 13 which may be made to 70 impinge against the lower portion of the clamp 11 so as to hold the latter in the required adjusted position.

From the seat portion 5 the tube 4 is offset laterally as at 14 and then extended 75 into an exteriorly threaded attaching portion 15 having a coupling sleeve 16 adjustably mounted thereon and provided with a bottom flange 17 which may be advanced against a sealing gasket 18 and thereby 80 cause the latter to be yieldingly engaged against the flange 19 of a nipple 20. The nipple carries a neck 21 to which one end of a hose 22 is connected. The opposite end of the hose is connected through a 85 coupling 23 with a short pipe 24 which extends from the bottom of the attaching end 25 of the draw-off faucet 26. The pipe 24 carries a suitable pet cock 27 by means of which communication between the gage 90 tube 4 and the cask 28 may be cut off when desired.

From this construction it is seen that the level of the liquid within the cask 28 will be clearly visible through the gage 95 tube 4 and the quantity of the liquid may be thus measured accurately during the operation of drawing the liquid from the cask. Owing to the simplicity of the device it may be applied to casks or liquid receptacles of any standard formation and then connected with the draw-off portion 26 without requiring any great changes in the construction of the latter.

From the foregoing description, taken 105 in connection with the accompanying drawings, the construction and operation of the invention will be readily understood without requiring a more extended explanation.

11 Various changes in the form, proportion and the minor details of construction may

2
be resorted to without departing from the principle or sacrificing any of the advantages of this invention, as claimed.

Having thus described my invention,
5 what I claim is:

A gage comprising a tube holder constructed from a single piece of metal stamped in its main length to provide a tube receiving channel, a tube mounted in 10 the channel, a seat closing the bottom of the channel, the said tube having an intake end offset from the seat and then extended downwardly therefrom, a nipple located

at the lower end of the tube, a coupling for advancing the nipple against one edge 15 of the tube, the tube holder having a graduated portion extending throughout the length of the tube channel, and a hose extending from said nipple and provided at one end with a coupling device.

20 In testimony whereof I affix my signature in presence of two witnesses.

PETER DRAUTZBURG.
